CLAIM

The ornamental design for a mirror cornice, as shown and described.

DESCRIPTION

FIG. 1 is a top and front perspective view of a first embodiment of a mirror cornice, showing my new design; FIG. 2 is a bottom/rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom and front perspective view of a second embodiment of a mirror cornice;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is an environmental top and front perspective view of the mirror cornice of FIG. 1;

FIG. 15 is a front view thereof;

FIG. 16 is a rear view thereof;

FIG. 17 is a left side view thereof;

FIG. 18 is a right side view thereof;

FIG. 19 is a top view thereof;

FIG. 20 is a bottom view thereof;

FIG. 21 is an environmental top and front perspective view of the mirror cornice of FIG. 1;

FIG. 22 is a front view thereof;

FIG. 23 is a rear view thereof;

FIG. 24 is a left side view thereof;
 FIG. 25 is a right side view thereof;
 FIG. 26 is a top view thereof;
 FIG. 27 is a bottom view thereof;
 FIG. 28 is an environmental top and front perspective view of the mirror cornice of FIG. 1;
 FIG. 29 is a bottom/rear perspective view thereof;
 FIG. 30 is a front view thereof;
 FIG. 31 is a rear view thereof;
 FIG. 32 is a left side view thereof;
 FIG. 33 is a right side view thereof;
 FIG. 34 is a top view thereof;
 FIG. 35 is an environmental top and front perspective view of the mirror cornice of FIG. 8;
 FIG. 36 is a bottom/rear perspective view thereof;
 FIG. 37 is a front view thereof;
 FIG. 38 is a rear view thereof;
 FIG. 39 is a left side view thereof;
 FIG. 40 is a right side view thereof; and,
 FIG. 41 is a top view thereof.

The dot-dot broken lines in the drawings depict environmental subject matter and form no part of the claimed design.
